PROCESS FOR THE PRODUCTION OF VALUABLE HYDROCARBON PRODUCTS BY THE EXTRACTION OF SOLID CARBONACEOUS MATERIALS

Mathias Pier, Heidelberg, and Ernst Donath, Mannheim, Germany, assignors to Standard I. G. Company, Linden, N. J., a corporation of Delaware

Application July 21, 1937, Serial No. 154,920
In Germany July 23, 1936

5 Claims. (Cl. 196—14)

The present invention relates to a process for the treatment with hydrogenating gases, especially to the destructive hydrogenation of extraction products of solid carbonaceous materials, 5 to produce valuable hydrocarbon products and more particularly to an improved method of working up the extraction products.

The extraction of solid carbonaceous materials, such as bituminous coal, brown coal, peat and the like, with organic solvents is usually carried out under high pressure and at elevated temperatures. After the extraction, the mixture of solvent and extract obtained is usually first mechanically freed from solid substances, for example, by filtering or centrifuging, and the solvent is then removed from the mixture by distillation. The remaining extract is a useful initial material for the production, by treatment with hydrogenating gases, of hydrocarbon oils 20 such as gasoline, Diesel oil, lubricating oil and the like, and for such destructive hydrogenation, it may be diluted with heavy or middle oil.

We have ascertained that, due to the great reactivity of the extracted products, the removal 25 of the solvent by distillation causes substantial alterations, for example, polymerizations, of the constituents of the extract, which alterations in turn cause undesirable disturbances when the extract is used, for instance as fuel oil, or preferably when it is subsequently treated with hydrogenating gases. These disturbances result in the lowering of the speed of the reaction and of the yield of the desired hydrocarbon products.

We have found that said undesired alterations 35 of the extracted products are avoided, with the result that the subsequent treatment with hydrogenating gases is substantially improved, if the removal of the solvent from the mixture of extract and solvent by distillation is only carried out after the addition of an organic diluent, the boiling point of which is higher than that of the solvent. The addition of the diluent prior to the removal of the solvent prevents superheating of the extract during the distillation and thus allows of the extract being obtained substantially 45 in its original reactive state without alterations of its quality. The remaining mixture of extract and diluent may then be subjected to the treatment with hydrogenating gases, for example, destructive hydrogenation, if desired or necessary after further dilution with middle and/or heavy oil.

The extracts suitable for treatment in accordance with the present invention are suitably obtained by treating finely ground bituminous coal,

brown coal or peat with a solvent, such as, for example, tetrahydronaphthalene or mixtures thereof with phenols, for instance with cresols, or lower fractions of a middle oil, at temperatures between 250° to 479° centigrade, preferably between 400° and 460° centigrade, advantageously in the presence of catalysts and, if desired, under pressure and/or in the presence of limited amounts of hydrogen, and, if desired, in several stages in which increasing temperatures and/or pressures may be employed. The extraction may be carried out as a batch process or in continuous or intermittent operation. The resulting mixture of extract and solvent is freed from solids, such as ash, by mechanical means, for example, by filtration or centrifuging, and a suitable organic diluent of high boiling point is then added, for example, upper middle oil and/or heavy oil fractions of tar or of hydrogenation products from another portion of such extract 20 or from solid carbonaceous materials. Sometimes it may be desirable to add a part or a whole of the diluent prior to or during the mechanical separation of solids, or to pass diluent to the separator to wash the residue. The solvent is 25 then distilled off and the remaining mixture of extract and diluent may be subjected to a treatment with hydrogenating gases, such as hydrogen or gases containing or supplying sufficient free hydrogen, for example, a destructive hydrogenation, if desired, after addition of further amounts of oils of high boiling point, in the presence of catalysts at temperatures above 250° centigrade, say above 280° centigrade, for example, at from 300° to 500° centigrade and under a pressure of 30 20, 50, 100, 200, 300, 500 or 1,000 atmospheres or more.

The catalysts may be dispersed within the initial material or stationarily contained in the reaction vessel. Suitable catalysts are, for example, oxides and sulphides of heavy metals, such as tungsten, molybdenum, iron, chromium and the like. Tin or zinc, more particularly in the form of salts of organic acids of low molecular weight may likewise be employed. The catalysts may be activated by promoters such as difficultly reducible oxides of metals, for example, thorium or cerium, and be supported on carriers, for example, activated brown coal small coke, alumir or bleaching earth.

According to the particular conditions applied in the treatment with hydrogenating gases and to the nature of the initial material, gasoline, middle oil, Diesel oil, fuel oil, heavy oil, lubricating oil and/or paraffin wax may be obtained.

- By a suitable regulation of the course of this operation the diluent may be recovered from the reaction products in an amount corresponding to the quantity used for the dilution of the mixture of extract and solvent, so that the diluent may be used again in the treatment of a fresh mixture of extract and solvent. Similarly, the solvent which has been recovered by distillation may also serve again for the extraction of a fresh portion of initial solid carbonaceous material.
- The treatment with hydrogenating gases is usually carried out as a continuous process, although batch operations or intermittent operations may be applied.
- The following example and the drawing, which is a diagrammatic illustration in partial sectional elevation of suitable equipment for carrying out this process and which indicates the flow of materials, will further illustrate how the invention is carried out in practice, but the invention is not limited to said example. The parts are by weight unless otherwise stated.

Example

- Gas flame coal is admixed with 1.5 times its weight of a mixture of 80 per cent of tetrahydronaphthalene and 20 per cent of cresol. The whole is heated at 400° centigrade during two and a half hours under a pressure of 100 atmospheres. 85 per cent of the organic substances contained in the coal are thus dissolved. The resulting solution is freed from solid matter, such as ash, by filtration. 1.2 parts of heavy oil obtained from bituminous coal and containing 15 per cent by volume of components boiling below 325° centigrade are added for each part of the solution and the mixture is subjected to distillation at a temperature up to 260° centigrade, measured with an instrument immersed in the liquid; tetrahydronaphthalene and cresol and naphthalene formed from tetrahydronaphthalene during the extraction, are distilled off. The remaining mixture of extract and diluent is then subjected to destructive hydrogenation with hydrogen under a pressure of 600 atmospheres, at 420° centigrade, in the presence of 0.06 per cent (calculated on the amount of extract) of tin oxalate and 0.9 per cent (calculated on the amount of extract) of ammonium chloride. From 100 parts of extract there are obtained 14 parts of gaseous hydrocarbons and 86 parts of a liquid which is free from asphalt and consists of an oil suitable as Diesel oil, in admixture with a small amount of gasoline.

If the mixture of extract and solvent be subjected to distillation for the removal of tetrahydronaphthalene and cresol without the addition of heavy oil, the destructive hydrogenation must be carried out with a lower speed in order to obtain a sufficient conversion of the initial material, but nevertheless a larger amount of gaseous hydrocarbons is formed, so that the yield of liquid products is substantially lower.

We claim:

1. A process for the production of valuable hydrocarbon products from products obtained by extracting solid carbonaceous materials with organic solvents, which comprises adding an organic diluent, the boiling point of which is higher than that of the solvent, to the mixture of extract and solvent, subjecting the diluted mixture to distillation, thus expelling the solvent and subjecting the remaining mixture of extract and diluent to a treatment with hydrogenating gases.

2. A process as claimed in claim 1 in which the treatment with hydrogenating gases is a destructive hydrogenation which is carried out at temperatures between 300 and 500° centigrade and at a pressure above 200 atmospheres.

3. A process as claimed in claim 1 in which the treatment with hydrogenating gases is carried out in such a manner that the amount of diluent recovered from the reaction products corresponds to the quantity used for the dilution of the mixture of extract and solvent, and using the recovered diluent for the treatment of a fresh mixture of extract and solvent.

4. A process as claimed in claim 1 in which the upper fractions of a middle oil are employed as a diluent.

5. Process for the manufacture of hydrocarbon oils and gases from coal, which comprises heating the coal with an organic solvent which is capable of dissolving part of the coal, freeing the solution so obtained from the undissolved residue of the coal, adding to the solution an organic diluent medium which boils at a temperature higher than the boiling point of the organic solvent, then removing the solvent in vapor form, and subjecting the extracted fraction of the coal while mixed with said organic diluent medium to hydrogenation in the presence of a hydrogenation catalyst at an elevated temperature adapted to hydrogenate the extracted fraction to liquid oils, and under a pressure higher than atmospheric.
